BRAKE BEAM SUPPORT CHAIR

Edwin G. Busse, Chicago, Ill., assignor to Chicago Railway Equipment Company, Chicago, Ill., a corporation of Illinois

Application December 24, 1934, Serial No. 758,986

16 Claims. (Cl. 188—213)

This invention relates to guards, guides, or supports for railway brake beams and consists particularly in novel chair structure for providing a sliding bearing between the beam and an underlying guard, guide, or support strap.

Where a brake beam is equipped with an underlying auxiliary third or fourth point guard, guide, or support, a separately formed bearing on the beam, called a chair or shoe, is usually provided to slidably engage a strap carried beneath the beam by the truck spring plank or other convenient part. Fourth point support chairs, in particular, should be adjustable angularly and laterally relative to the beam due to variations in the shape, height, and position of the support strap, height of the beam, etc. A simple bearing element or chair having pivoted or flexing jaws for gripping the tension member of the brake beam is usually provided so as to facilitate the necessary adjustment.

It has been found that this simple type of fourth point support chair tends to rotate on or slide along the tension member in spite of the clamping elements, thus working off from the support strap so as to become inoperative. Special hand wrenches and power tools have proven unavailing for properly seating the chair clamp and where the chair is improperly tightened, as is frequently the case, this disadvantage is aggravated. Warpage in cast or forged chairs, which it is almost impossible to prevent, also hastens the loosening of the chair so as to render the same ineffectual. Special tapered clamping pins and bolts have failed to overcome the above difficulty as have inserts of hardened steel and serrated structure applied to the clamp jaws for biting into the metal of the tension member.

Fourth point support chairs attached to both the tension and compression members of the beam will remain rigid therewith, but such a chair cannot be adjusted and for this reason is not particularly desirable. Deformed and angular tension members are undesirable for the same reason.

In case of third point supports, a chair, similar to the simple form of fourth point chair referred to above, is clamped to a round pin immovably seated in special lugs or ears projecting from the front end of the strut. This chair also tends to rotate on the ear pin due to constant vibration.

In a copending application Serial No. 755,686, filed December 3, 1934 in the names of Edwin G. Busse and Herbert W. Ekholm, is illustrated a universal form of third point support chair which may be securely and rigidly fastened to

a truss type beam without a special strut, but this chair is somewhat more complicated than the simple clamp type chair.

One object of the present invention is to provide a brake beam support chair which can be easily applied to brake beams so as to retain its proper adjustment indefinitely.

Another object is to provide a brake beam support chair which can be rigidly and permanently clamped to the beam, but which may be freely adjusted as required.

Another object is to provide a novel adjustable brake beam support chair which will retain its proper adjustment and position on the beam even though improperly tightened.

These objects and other more detailed objects are attained substantially by applying between the third or fourth point support chair jaws and the part of the brake beam clamped therebetween, a frictional insert formed of material, such as rubber, having a substantially higher coefficient of friction with the metal of the beam part than the metal clamping jaws, as opposed to structure depending for its gripping power upon hard or sharp elements which penetrate the surface of the tension member.

In the accompanying drawings illustrating the invention—

Figure 1 is a top view of a part of a railway truck spring plank and truss type brake beam. 30

Figures 2, 6, 9, 11, 12, 13, 14, 15, and 17 are vertical sections through brake beam third and fourth point support chairs illustrating various forms of the invention.

Figure 3 is a transverse section taken on the line 3—3 of Figure 2. 35

Figures 4 and 5 are views corresponding to Figure 3 but illustrating modifications.

Figure 7 is a horizontal section taken on the line 7—7 of Figure 6. 40

Figure 8 is a detail view of a modified form of frictional insert.

Figure 10 is a side view of a portion of the beam tension member in Figure 9.

Figure 16 is a sectional view of another form of frictional insert. 45

Figure 18 is a detail view of one of the inserts in Figure 17.

Figure 19 is a top view illustrating a third point support chair embodying the invention, 50 the brake beam being illustrated in dot and dash lines.

Figure 20 is a side view, sectioned in part, of the chair in Figure 19.

Figure 21 is a vertical section illustrating 55

another form of third point support chair and is taken on the line 21—21 of Figure 22.

Figure 22 is a top view of the third point support chair in Figure 21.

Figures 23 and 24 are partial views, partly sectioned, of brake beam support chairs embodying still other forms of the invention.

Figures 25 is a sectional view taken on the line 25—25 of Figure 24.

Figure 1 illustrates a brake beam including the compression member 1, strut 2 having a slot 3 and pinholes 4 for the usual brake lever (not shown), and tension member 5 of cylindrical or round section. Attached to the spring 15 plank 6 by means of the brackets 7 are the fourth point guard, guide, or support straps 8 extending beneath the brake beam between the strut 2 and the brake heads (not shown) at each end thereof. Clamped to the tension member 5 by means of clamping bolts 9a are the fourth point support chairs or shoes 9 which slidably engage the straps 8.

The fourth point support chair, shown detailed in Figure 2, includes the enlarged bearing portion 10 for engaging the underlying support strap and the pivoted arcuate jaws 11 and 12 pinned together at 13. At the upper extremities of the jaws 11 and 12 are the apertures 14 and 15 for receiving a bolt (see Fig. 1) for clamping the jaws 11 and 12 about the beam tension member 5. The inner surfaces of the jaws 11 and 12 are recessed and provided with the inserts 17 and 18, preferably of live rubber, for engaging the tension member to assist in maintaining the chair rigidly assembled therewith.

The jaw recesses are preferably undercut, as at 19 (Fig. 3), and the rubber inserts made of tapering form, as the insert 18, so as to be self secured therein. The inserts are compressed in application to the jaw recesses. The inserts 17 and 18 may be specially molded or formed of flat strip material, and preferably will be distorted longitudinally and laterally and also flexed in insertion into the jaw recesses so as to be securely held therein.

Figure 4 illustrates another manner attaching the inserts to the support chair jaws. In Figure 4 the insert 20 is attached within the recess 21 in the jaw 22 by means of a rivet 23. The recess 21 is substantially larger than the insert 20 so as to permit expansion of the insert under pressure.

In Figure 5, the insert 24 is attached to the chair jaw 25 by a glue or cement substance 26.

Figures 6 and 7 illustrate another type of frictional insert applied to the pivoted jaws 27 and 28 of a support chair. The pivoted jaws have interengaging lugs 29 and 30 receiving the pin 31. The inserts 32 and 33 have interengaging apertured lugs 34 and 35 through which the pin 31 also extends for securing the inserts 32 and 33 within the recesses 36 and 37 in the chair jaws. The inserts 32 and 33 are provided with the suction cups or recesses 32a and 33a for increasing the frictional resistance between chair jaws and the clamped beam member. If desired, the inserts 32 and 33 may be formed integrally as the jaws 38 and 39 in Figure 8, having an apertured lug 40 for receiving the pivot pin to secure the insert in position. Jaw recesses 36 and 37 provide for expansion of the inserts 32 and 33, as in Figures 3, 4, and 5.

In Figure 9, the beam tension member 41 is recessed at 42 and provided with a frictional

insert 43, preferably of rubber, which is disposed to be engaged by one of the pivoted jaws 44 of the fourth point support chair generally indicated at 45. The chair in this form of the invention will be as rigidly secured in position as the chairs in the previous forms, but cannot be adjusted longitudinally of the tension member unless the insert 43 is made of substantial length.

In Figure 11, one of the pivoted jaws 46 of the fourth point support chair has a restricted undercut recess 47 within which is applied the frictional insert 48 which is distorted in application thereto so as to be self maintained within the recess. The other jaw 49 is deformed, as at 49a, and provided with an undercut recess 50 within which is applied the bulbous nubbin portion 51 of the frictional insert 52. The nubbin 51 secures the insert within the jaw recess.

In Figures 12, 13, 14, and 15, the fourth point chair is formed as a unitary metal member having flexible jaws. In Figure 12, the jaw portions 53 flex about the narrow neck 54 connecting the same with the bearing portion 55 of the chair. Frictional insert 56, also formed in one piece, has a bulbous nubbin 57 applied to the undercut recess 58 in the lower part of the shoe. In Figure 13, the insert 59 is formed of a strip of rubber and is crimped at 60 to form a bulbous projection for application to the undercut recess 61 in the lower part of the chair 62. In Figure 14, the insert 63 has a lug 64 provided with an aperture 65 by means of which the insert may be pinned within the recess 66 in the lower part of the support chair 67. In Figure 15, each jaw 68 is provided with a rubber insert 69 with a portion compressed within the undercut recess 70 of the jaw and another portion terminating in the recess 71 in the lower part of the chair. The inserts are secured to the chair jaws by rivets 72. In each of Figures 12, 13, and 14, the rubber inserts are self secured to the chair, but these may be additionally cemented or riveted thereto if desired.

Figure 16 shows another frictional insert 73 formed as a portion of a circle and having suction cups 74, as in Figure 6. The insert is cemented or riveted to the chair jaws.

In Figures 17 and 18, the jaws 75 have bosses 76 with apertures 77 enlarged at their outer ends for receiving the button-like head portions 78 of the projections 79 on the inserts 80 and 80a. This type of insert may be easily snapped into position in the jaw recesses. The recess 75a in the right hand jaw is larger than the insert 80a received therein, as in Figures 4 and 5, to permit expansion of the insert under pressure. The insert 80a also has suction cups 80b, as in Figures 6 and 16. Preferably the inserts in both jaws will be identical in practice.

Figures 19 and 20 show in broken lines the front extremity of a brake beam strut 81 having ears or lugs 82 projecting forwardly of the tension member 83. Clamped to the pin 84 extending between the ears 82 is a third point support chair having clamping jaws 85 and 86 and a pivoted lower portion 87 for resting upon an underlying supporting strap (not shown). The jaws 85 and 86 are provided with rubber inserts 88 for frictionally engaging the pin 84 and preferably compressed or otherwise distorted in insertion into the jaw recesses so as to be self maintained therein. The chairs in each of the described figures may be used with either third or fourth point supports.

Figures 21 and 22 show a different type of

third point support chair as more clearly illustrated and described in the above-mentioned copending application Serial No. 755,686, filed December 3, 1934. The chair includes a broad bearing portion 89 for engaging the guard, guide, or support strap 90 and rigid jaws 91 and 92 for receiving the beam tension member 93 therebetween and apertured for receiving the extremities of U-bolt 94 secured therein by the nuts 95 and for clamping about the beam strut 96. Applied to a suitable undercut recess 97 in the inner surface of each pair of jaws is a rubber insert 98 for frictionally engaging the tension member 93 and having a projection 99 with an enlargement 100 to be inserted through the aperture 101 for securing the insert in position.

In each of Figures 23, 24, and 25 one jaw only is shown of a support chair similar to that in Figure 2. The jaw 102 in Figure 23 has a cylindrical pocket 103 receiving the coiled spring 104 and the boss 105 on the insert 106. Insert 106 engages shoulders 107 on the chair jaw to maintain the assembly with spring 104 under compression.

In Figures 24 and 25, the jaw 108 has a laterally elongated pocket 109 receiving the flexed strip spring 110 which bears against and is secured to the insert 111. As in Figure 23, the insert is disposed to yieldingly engage the gripped beam part so as to maintain the beam and chair tightly assembled in case of loosening of the clamping bolt or bending of the chair jaws due to vibration and constant pressure. Also the yielding or resilient spring pressed inserts facilitate attachment of the chair to a beam part which is too small for the chair jaws. The resiliently mounted inserts are preferably of frictional material as in the previous forms.

The novel pliable or resilient inserts will hold the chairs rigidly in position even though the clamp is not fully tightened. The inserts do not deteriorate rapidly, as might be supposed, the applicant having successfully utilized live rubber at least fifteen years old for this purpose. But even though the inserts should deteriorate or be lost or removed, the metal jaws would still function as satisfactorily as the old type chairs.

The novel chair has another advantage in that in case the clamping bolt becomes very loose, the inserts will prevent or reduce rattling.

Live rubber inserts are preferable due to the high coefficient of friction between rubber and metal, but other substances might be used, such as various rubber compositions, which also have higher coefficients of friction with the metal of the beam tension rod than the metal jaws of the chair clamp. The inserts as shown may be formed of molded or strip material. The invention may also be applied to chairs for application to beam parts of non-cylindrical shape for resisting longitudinal slippage of the chair.

The invention is not limited to the details of the various forms illustrated and described and the exclusive use of all modifications that come within the scope of the appended claims is contemplated.

I claim:

1. A brake beam support chair including interconnecting parts for clamping a brake beam member between them, each of said parts having a recess, and a yielding element in each recess for engaging the beam member to assist in

maintaining the chair and beam properly assembled.

2. In combination, a brake beam member, support chair jaws clamped to said beam member, and frictional inserts compressed between said member and each of said jaws for maintaining the same properly assembled.

3. In combination, a brake beam including a cylindrical portion, a support chair having jaw portions for clamping around said beam portion, and readily compressible inserts substantially lining said jaw portions for engaging said beam portion to assist in maintaining said chair and beam properly assembled, said cooperating portions of the chair and beam permitting manual angular adjustment of said chair.

4. A brake beam support chair including parts for enclosing a brake beam, said part having a rubber insert for substantially lining said parts for engaging the beam to assist in maintaining the chair properly positioned.

5. A fourth point brake beam support chair including a part for gripping the tension member of a brake beam, said part including a rubber insert for substantially surrounding the tension member to increase the frictional resistance between the same and the chair.

6. A brake beam support chair including a part for attachment to a brake beam cylindrical member, said chair part having a recess in its inner surface, and a rubber-like insert in said recess for assisting in resisting slippage between the beam and chair, said insert being of resilient material and having an integral portion interengaged with said chair part so as to maintain itself therein at all times.

7. A brake beam support chair having a part for clamping to a brake beam member, said part having recesses on opposite faces, and a rubber insert applied to one of said recesses for engaging the beam to assist in resisting slippage of the chair, said insert including a retaining portion projecting through said part into the other of said recesses.

8. A brake beam support chair having a part for clamping to a brake beam member, said part having a restricted aperture, and a rubber insert applied to said part for engaging the beam to assist in resisting slippage of the chair, said insert having an enlarged part which is compressed for insertion through said recess and then expands so as to secure said insert in position.

9. A brake beam support chair including a part for attachment to the beam, said part having a recess, and a rubber insert applied to said part for engaging the beam to resist slippage of the chair, said insert having a lateral projection with an enlargement at its extremity adapted to be distorted in insertion through said recess and to overlap said recess in the assembled position to maintain said part and insert properly assembled.

10. A brake beam support chair having a part including jaws for clamping to a brake beam member, an element pivotally connecting said jaws, and a frictional insert applied to said part for engaging the beam to assist in resisting slippage of said chair, said insert being secured to said pivot element.

11. A brake beam support chair having a part for clamping to a brake beam member, said part having a recess, and a rubber insert secured in said recess for engaging the beam to assist in resisting slippage of the chair, there

being space in said recess permitting spreading of said insert under pressure.

12. A brake beam third point support chair including means for attachment to structure at the front of the beam, said means including a frictional insert element for engaging the beam to assist in maintaining the chair properly positioned.

13. In combination, a brake beam including a strut with third point support ears, a pin between said ears, and a third point support chair clamped to said pin, there being a rubber element between said pin and said chair for resisting slippage therebetween.

14. A brake beam support chair having opposed resilient friction elements for gripping

opposite sides of a beam part, each of said elements having suction cups on its beam engaging surface.

15. A compressible friction pad for a railway brake beam support chair clamp comprising a clamp-lining portion for engaging a beam member, a projection on the rear of said portion for extending through the clamp, and a button-like head on the end of said projection for retaining the pad in the clamp. 10

16. A compressible friction pad for a railway brake beam support chair clamp comprising an elongated clamp-lining portion for engaging a beam member, and relatively restricted means for retaining the pad in the clamp. 15

EDWIN G. BUSSE.
